PAIR OF SPECTACLES

Jack Bloch, Leominster, Mass., assignor to Foster Grant Co., Inc., Leominster, Mass.

Filed Oct. 12, 1970, Ser. No. 25,462

Term of patent 14 years

Int. Cl. D16—06

U.S. Cl. D57—1

FIG. 1

FIG. 2

FIG. 1 is a front elevational view of a pair of spectacles showing my new design;

FIG. 2 is a top plan view thereof;

FIG. 3 is a side elevational view thereof.

The side not shown has substantially the same appearance as the side shown.

I claim:

The ornamental design for a pair of spectacles, substantially as shown and described.
